PAPER FEED

John T. Ferry, Ilion, N. Y., assignor to Remington Rand Inc., Buffalo, N. Y., a corporation of Delaware

Application September 2, 1942, Serial No. 456,989

9 Claims. (Cl. 271—51)

This invention relates to new and useful improvement in devices for feeding paper, and particularly to paper feed rolls and associated parts.

It is the main object of the invention to so form and construct paper feed rolls that fragments, bits, and "chips," separated from the paper passing through the machine, will not collect on the rolls and tend thereby to impair the feed of the paper through the machine.

Broadly and generally stated the problem which has been solved by the present invention is (1) to provide means inherent in the feed rolls so that the "chips" cannot adhere thereto, and (2) to construct the paper feed rolls so that fragments, bits and "chips" of paper coming into contact therewith will not have a planar contact with the surface of the rolls, but only a "point" contact therewith. Therefore, the "chips" being charged with static electricity as they usually are, will not cling to the surface of the rolls as they do when there is a planar contact between the roller and the "chips."

The particular embodiment of the problem which confronted the applicant has to do with card perforators in which cards are fed through the machines, to be punched or perforated in various manners and in accordance with various codes to represent business data which would later be tabulated for statistical purposes. In this particular type of machine, the cards are fed from a hopper and by rolls led into a chamber in which they are held while being punched or perforated. Upper and lower rolls engage the cards while they are in this chamber not only to feed them thereto, but also to eject them from the chamber when they are released after being punched.

In the operation of the machine, after a card has been introduced into the card chamber and is positioned to be punched, the chamber with the card is moved upwardly in a manner to achieve the perforating of the cards, but at this step in the operation the lower feed rolls are left behind and are disposed below the chamber. As the card is perforated the "chips" or fragments punched therefrom will fall down, and in actual previous practice and use they dropped onto the lower feed rolls and, being charged statically with electricity, they had a very annoying tendency to stick to the rolls, especially along the sides thereof. It was found, therefore, that when, in the next operation of the machine, the card chamber was lowered and the cards again brought into contact with the rolls, that the "chips" clinging thereto would tend to be fed

up by the rolls into the card chamber to prevent the feed of the cards and also to impair the proper registration of the cards in the chamber. Since the feed of the cards into and out of the chamber and the registration of the card in the chamber are very important matters in the proper code punching of the cards, this disadvantage posed a very serious and important problem.

In studying this problem it was realized that 10 when the "chips" separated from the paper being fed through the machine and came into contact with the ordinary flat surfaced rolls, the "chips," being flat themselves, could and did have a planar contact with the smooth surfaces thereof 15 which enabled them better to cling thereto and result in the above mentioned difficulties. It was then realized, after careful study, that if the surfaces of the rolls with which the "chips" might contact were provided with non-planar 20 surfaces, the plane to plane contact could not result and the difficulties hitherto encountered would be overcome. Therefore, in accordance with my invention I provide the rolls with non-planar surfaces, so that any "chips" which might 25 contact the rolls and/or associated parts can have only a point-to-point contact therewith and thus reduce to a minimum the chance of the "chips" clinging to the rolls and their associated parts with the deleterious results previously mentioned.

30 In order to show a present preferred embodiment of my invention, which, however, is only one form which it may assume, I have presented several drawings illustrating the invention as applied to a particular form of card punch machine of the well known Powers type, of which an example may be seen in U. S. Patent No. 2,044,707, issued June 16, 1936, to W. W. Lasker.

Further and more specific objects, features, and advantages will more clearly appear from a 40 consideration of the following description, especially when read in connection with the accompanying drawings, which illustrate a present preferred embodiment of the invention, wherein

Fig. 1 is a cross section through a card perforator, showing the invention;

Fig. 2 is a view similar to Fig. 1 somewhat enlarged showing a portion of the machine with the parts in the position at which the cards are being perforated;

Fig. 3 is an enlarged detail side elevation of 50 the feed rolls; and

Fig. 4 is a cross section taken on the line 4—4 of Fig. 3.

In the specific form of embodiment illustrated 55 in the drawings, the paper, in this case in the form

of cards A to be punched or perforated, is stacked in the magazine 10, and is fed seriatim through a preadjusted card throat 11 by a harmonically reciprocated card picker 12 to the pairs of rotating feed rolls 14 and 15, thence through feed rolls 20a and 20 into the card punching chamber 16. This chamber 16 consists of a pair of matched perforated plates, the lower one 17 serving as a die, and the upper one 18 as a stripper plate and guide for the punches. The card A to be punched is temporarily held stationary in the punching chamber 16 by a pair of cam and spring controlled card stops 19 against the transporting action of the rotating feed rolls 20 and 20a. The feed rolls 14, 15, and 20 are driven by a main shaft 22 through a suitable train of gearing in the well known manner.

The entire punching chamber 16, with the set of punches 21 (one for every possible perforating position), the card and punch guide support, is given a reciprocatory motion for every rotation of the main shaft 22 by a suitably contoured box cam 23 fixed thereon, acting through a forked lever frame 24, which is pivoted near its mid-points on trunnions 25 on the main frame. Above the punches 21 is a set of pins or gags 26, one for each punch, which are spring pressed upward and carried in a stationary frame. Mounted over the gags 26 is a plurality of set bars 27 having extrusions 28 thereon adapted to cooperate with locking slides 30.

Mounted in a carriage 31 is a set-bar basket, comprising a series of set-bar pins 32, which are connected by Bowden wires 33 to individual solenoids (not shown) controlled by contacts under the keys 34. The depression of a key 34 actuates a set pin 32, which in turn depresses a set-bar 27 over which it is positioned. The depressed set-bar 27 is locked down by the locking slide 30, thus preventing its associated punch gag element 26 from rising when the punches are raised. During the upward movement of the punching chamber 16 and its frame, the selected punches 21 are held stationary relative to the main framework by the gags 26, and are thus forced through the card in the punching chamber at the location determined by the corresponding holes in the matched perforated plate. The unselected punches are free to be raised by the card as shown in Fig. 2.

During the downward movement of the said parts, the punches 21 are arrested against continued downward movement by the fixed stripper plate 29 which is contacted by the heads of the descending punches 21. The card stops 19 are withdrawn and the feed rolls 20 and 20a, which are located at the extreme narrow margins of the punching chamber, feed the punched card to a pair of eject rolls 35 and thence to the storage receptacle 36.

The lower feed rolls 20 which, as shown, constitute an improved element of the paper feeding device, are formed as shown in Figs. 3 and 4. In this improved form the outer peripheries of the rolls are roughened or knurled to form "point" contact surfaces, as indicated by the numeral 37, so as not to present much, if any, flat surface to which statically charged paper "chips" may cling. Likewise, the side faces of the rolls are also formed with radial ridges or teeth 38 which slope from the center outwardly, and break up the surface of the sides of the rolls into a plurality of line surfaces for the same purpose. The hub 39 of the rolls has also been

treated in a similar manner, the ridges increasing in depth from the face of the rolls 20 outward as shown.

Referring to Figs. 1 and 2, it will be noted that when the punch frame is at rest (Fig. 1) the feed rolls 20 and 20a extend through slots in the die plate 17 in a position to receive and feed the card A forward against the card stop 19.

However, when the card chamber and the accompanying punches 21 are raised to effect punching of the cards, as before explained (see Fig. 2), the lower rolls 20 do not rise, but continue to rotate, lying, as shown, below the card frame and chamber 16. It is during the time that the rolls 20 are disposed below the card chamber 16 that the "chips" punched out of the cards tend to drop down onto the rolls 20, and being statically charged, tend to cling thereto, especially when the rolls present sizable flat areas to which the "chips" can adhere. If this happens, then, when the punch chamber 16 is lowered to the position shown in Fig. 1 again, the "chips" thus clinging, sometimes whole strings of them, to the rolls, would be carried into the card chamber 16, and tend to clog the card chamber and impair the proper positioning of the card against the stop 19, which would affect the proper registration and, consequently, the proper perforation of the card.

However, it is apparent that when the improved form of rolls 20 is used this adhesion of the "chips" to the rolls is practically eliminated and, therefore, the above mentioned disadvantageous results are avoided. In the improved rolls when the "chips" drop onto the rolls they find no planar contacts since practically the entire surface of the feed elements, including the rolls and their hubs, is formed with a large number of ridges and corrugated areas which present to the "chips" nothing but line or point contacts which efficiently prevents any adhesion.

As most all the parts in machines of this type are provided with a slight coating of oil, it is possible that the oil may increase the possibilities of adhesion even more than that caused by the static charges on the paper chips. With the present construction the ridges formed on the peripheries and sides of the rolls will not only form "point" contact surfaces but also cause an air current which will more readily dislodge the paper fragments than if the peripheries and sides were smooth.

It is obvious that the use of rolls of this improved form is not limited to the instant use or type of machine, but may find utility in any place where "chips," dust, lint, or other substances, subject to frictional static charges, are liable to adhere to a flat surface, such as that on printing press rolls, etc.

The invention has herein been described in detail and with respect to a present preferred form thereof, but is not to be limited to such details and forms, since many changes and modifications may be made in the invention without departing from the spirit and scope of the invention in its broadest aspects.

What I claim as new and desire to secure as Letters Patent is:

1. In a card punching device having paper feed hubbed rolls, the surfaces of the rolls and the hubs being provided with ridges to prevent the paper fragments from clinging to the rolls and the hubs.

2. In a card punching device having paper feed rolls, the side surfaces of the rolls being provided with radial ridges to prevent paper fragments from clinging to the rolls.

3. In a card punching device having paper feed rolls, the side surfaces of the rolls being provided with radial ridges and the periphery of the rolls being knurled to prevent paper fragments from clinging to the rolls.

4. In a card punching device having paper feed rolls with hubs, the side surfaces of the rolls being provided with radial ridges, the peripheries of the rolls being knurled and the hubs having longitudinal ridges thereon increasing in depth from the rollers outwardly, the knurling and the ridges being provided to prevent paper fragments from clinging to the rolls.

5. In a device for punching cards having a chamber through which the paper is fed, feed rolls extending into said chamber to engage and feed the paper, means for lifting said chamber above the rolls during the operation of the device, and a plurality of ridges formed on the rolls to prevent fragments of paper falling out of the chamber from clinging to the rolls when disposed below said chamber.

6. In a device for punching cards having a chamber through which the paper is fed, hubbed feed rolls extending into said chamber to engage and feed the paper, means for lifting said chamber above the rolls during the operation of the device, the rolls being provided with lateral radial ridges and the hubs being provided with longitudinal ridges to prevent paper fragments falling out of the chamber from clinging to the rolls.

7. In a device for punching cards having a chamber through which the paper is fed, hubbed feed rolls extending into said chamber to engage and feed the paper, means for lifting said chamber above the rolls during the operation of the device, the rolls being provided with peripheral and lateral ridges and the hubs being provided with longitudinal ridges increasing in depth outwardly from the rolls to prevent paper fragments falling out of the chamber from clinging to the rolls or the hubs.

8. In a card punching device, paper feed rolls having point contact surfaces of definite areas on their peripheries and sides adapted to prevent paper fragments of greater areas, derived from the punching, from clinging to the rolls.

9. In a card punching device, paper feed rolls having knurled surfaces on their peripheries, and approximate radial ridges on their sides adapted to prevent statically charged paper fragments, derived from the punching, from clinging to said rolls.

JOHN T. FERRY.
